United States Patent Office

Des. 217,759
Patented June 9, 1970

217,759

CLOSURE FOR A CONTAINER

Jay F. Schweickart, Lancaster, Ohio, assignor to Anchor Hocking Corporation, Lancaster, Ohio, a corporation of Delaware

Filed July 29, 1968, Ser. No. 12,934

Term of patent 14 years

Int. Cl. D9—02

U.S. Cl. D9—275

FIG. 1 is a side elevational view of a closure for a container, showing my new design;

FIG. 2 is a front elevational view thereof;

FIG. 3 is a top plan view thereof;

FIG. 4 is a side elevational view of another embodiment thereof, and

FIG. 5 is a sectional view taken along line 5—5 on FIG. 4.

I claim:

The ornamental design for a closure for a container, substantially as shown and described.
